Specification for Design.

Patented Feb. 5, 1918.

Application filed June 12, 1915. Serial No. 33,830. Term of patent 14 years.

To all whom it may concern:

Be it known that we, JOHN E. DIETZ and WILLIAM TRAVERS JEROME, citizens of the United States, residing at New York, in the county and State of New York, are the executors of the last will and testament of FRED DIETZ, deceased, that the said FRED DIETZ did invent a new, original, and ornamental Design for a Lantern-Globe, of which the following is a specification.

The accompanying drawing represents in Figure 1 a front elevation and in Fig. 2 a

side elevation of a lantern globe showing the design.

We claim:

The ornamental design for a lantern globe as shown.

JOHN E. DIETZ.
WM. TRAVERS JEROME.

Witness as to John E. Dietz:

FRED H. TWOMBLY.

Witness as to Wm. Travers Jerome:

C. HENRY SPOLANDER.
